HERBICIDAL COMPOSITIONS CONTAINING URACIL THIOCYANATE ADDITION COMPOUNDS

Raymond W. Luckenbaugh, Wilmington, Del., assignor to E. I. du Pont de Nemours and Company, Wilmington, Del., a corporation of Delaware

No Drawing. Filed July 1, 1965, Ser. No. 468,956
4 Claims. (Cl. 71—2.5)

This application is a continuation-in-part of my co-pending application Serial No. 244,904, filed December 17, 1962, now abandoned.

This invention relates to improved herbicidal compositions containing novel uracil-thiocyanate addition compounds.

In accordance with the present invention it has been found that herbicidal uracils form novel addition compounds with certain metal thiocyanates which are herbicidal equivalents of the uracils per se but having superior properties for formulating into herbicidal compositions. The novel addition compounds for use in the present invention may be represented by the following formula:

where

R is alkyl of 1 through 10 carbon atoms, substituted alkyl of 1 through 8 carbon atoms, wherein said substituent is selected from the group consisting of bromine, chlorine, hydroxy, alkoxy, alkoxy carbonyl, dialkylamino, and cyano, aryl of 5 through 10 carbon atoms, substituted phenyl of 6 through 14 carbon atoms, wherein said substituent is selected from the group consisting of chlorine, bromine, fluorine, phenylalkyl of 1 through 6 carbon atoms, chloroalkoxy of 1 through 5 carbon atoms, trifluoromethyl, 1,2-tetramethylene, and 1,2-trimethylenylene, arylalkyl of 5 through 13 carbon atoms, substituted arylalkyl of 5 through 13 carbon atoms, wherein said substituent is selected from the group consisting of chlorine, nitro, alkyl and alkoxy, alkenyl of 3 through 8 carbon atoms, alkynyl of 3 through 8 carbon atoms, cycloalkyl of 3 through 12 carbon atoms, substituted cycloalkyl of 3 through 12 carbon atoms, wherein said substituent is selected from the group consisting of bromine, chlorine, methoxy and alkyl, cycloalkenyl of 4 through 12 carbon atoms, substituted cycloalkenyl of 4 through 12 carbon atoms, wherein said substituent is selected from the group consisting of bromine, chlorine, methoxy and alkyl, cycloalkyl alkyl of 4 through 13 carbon atoms, (substituted cycloalkyl)alkyl of 4 through 13 carbon atoms, wherein said substituent is selected from the group consisting of bromine, chlorine, methoxy and alkyl, cycloalkenyl alkyl of 5 through 13 carbon atoms, (substituted cycloalkenyl)alkyl of 5 through 14 carbon atoms, wherein said substituent is selected from the group consisting of bromine, chlorine, methoxy and alkyl,

R₁ is hydrogen, halogen, nitro, hydroxymethyl, branched or unbranched alkyl of 1 through 6 carbon atoms, or alkoxy methyl wherein alkoxy contains 1 through 4 carbon atoms;

R₂ is hydrogen, methyl, chloromethyl or bromomethyl;

2

R₃ is hydrogen or branched or unbranched alkyl of 1 through 4 carbon atoms;

X is oxygen or sulfur;

M is magnesium, calcium, strontium, or barium; and

n is 1 or 2,

with the proviso that R₁ and R₂ can be joined together to form an alkylene bridge of 3 through 5 carbon atoms.

It should be understood that the exact formulae of these uracil addition compounds are not known. On the basis of the best available information, it is believed the elements have the configuration shown in Formula 1, but it is intended that this invention embrace these addition compounds whatever their structure, and Formula 1 should therefore not be construed as limiting.

15 In Formula 1 the term "substituted alkyl" is intended to include such radicals as

bromoalkyl of 1 through 8 carbon atoms

chloroalkyl of 1 through 8 carbon atoms

20 hydroxyalkyl of 1 through 8 carbon atoms

alkoxyalkyl of 2 through 8 carbon atoms

alkoxy carbonyl alkyl of 3 through 8 carbon atoms

diaalkyl amino alkyl of 3 through 8 carbon atoms and

cianoalkyl of 2 through 8 carbon atoms

25 Similarly, the terms "aryl" and "substituted phenyl" embrace radicals such as

phenyl

naphthyl

O-biphenyl

30 pyridyl

chlorophenyl

bromophenyl

alkoxyphenyl

dibromophenyl

35 fluorophenyl

trichlorophenyl

alkylphenyl of 7 through 11 carbon atoms

dialkylphenyl of 8 through 12 carbon atoms

40 chloroalkylphenyl of 7 through 10 carbon atoms

nitrochlorophenyl

nitrophenyl

dichloronitrophenyl

chloroalkoxyphenyl of 7 through 11 carbon atoms

45 trifluoromethylphenyl

tetrahydronaphthyl and

indenyl

The terms "aralkyl" and "substituted aralkyl" are intended to include such radicals as

50 benzyl

phenylalkyl of 8 through 11 carbon atoms (total)

chlorobenzyl

dichlorobenzyl

alkylbenzyl of 8 through 11 carbon atoms (total)

55 dialkylbenzyl of 9 through 13 carbon atoms (total)

nitrobenzyl

alkoxybenzyl of 8 through 11 carbon atoms (total)

naphthylmethyl and

furfuryl

60 The terms "cycloalkyl," "cycloalkenyl," "cycloalkyl alkyl," and "cycloalkenyl alkyl" will include

cyclohexyl

cyclohexenyl

65 cyclohexylalkyl

cyclopentyl

cyclopentenyl

cyclopentylalkyl

cyclopentenylalkyl

70 norbornyl

norbornenyl

norbornylalkyl
 norbornenylalkyl
 bicyclo (2,2,2) octyl
 bicyclo (2,2,2) octenyl
 bicyclo (2,2,2) octylalkyl
 bicyclo (2,2,2) octenylalkyl
 cyclopropyl
 cyclobutyl
 cyclobutylalkyl
 cyclobutenyl
 cyclobutenylalkyl
 hexahydroindanyl
 tetrahydroindanyl
 hexahydroindenyl
 hexahydroindenyl alkyl
 tetrahydroindanyl alkyl
 hexahydroindanyl alkyl
 hexahydro-4,7-methanoindenyl
 hexahydro-4,7-methanoindanyl
 hexahydro-4,7-methanoindanyl alkyl
 hexahydro-4,7-methanoindanyl alkyl
 hexahydro-4,7-methanoindanyl alkyl
 decahydronaphthyl
 decahydronaphthyl alkyl
 tetrahydronaphthyl
 tetrahydronaphthyl alkyl
 decahydro-1,4-methanonaphthyl
 decahydro-1,4-methanonaphthyl alkyl
 octahydro-1,4-methanonaphthyl
 octahydro-1,4-methanonaphthyl alkyl
 decahydro-1,4,5,8-dimethanonaphthyl
 decahydro-1,4,5,8-dimethanonaphthyl alkyl
 octahydro-1,4,5,8-dimethanonaphthyl and
 octahydro-1,4,5,8-dimethanonaphthyl alkyl

These cyclic substituents can be further substituted with alkyl groups of 1 through 4 carbon atoms, methoxy, chlorine and bromine.

The above-described addition compounds are prepared by reacting the appropriate uracil with a suitable thiocyanate.

The uracil reactants are prepared according to the following equations:

(2)

(3)

(4)

The 1-alkyl substituted uracil reactants are then prepared from these tri-substituted uracils by ordinary substitution reactions with alkyl sulfates.

Preparation of suitable uracil reactants is set forth in greater detail in copending application Serial No. 364,309, 75

filed May 1, 1964. Those portions of that application showing preparation of suitable uracil reactants is incorporated by reference into this application.

The compounds of the invention are prepared by mixing 4 to 16 parts by weight of a 35-60% aqueous solution of a thiocyanate with a dry uracil at room temperature. Reaction is immediate. The addition compounds precipitate and are filtered from the reaction medium. They are then washed with an organic solvent such as ether or pentane and dried in vacuo over a dehydrating agent such as P_2O_5 or CaCl_2 .

The uracil-thiocyanate addition compounds hereof have a herbicidal effect similar to that of the uracils per se. These addition compounds have been found, however, in accordance with the present invention to provide important formulating and handling advantages and thus herbicidal compositions of these compounds are preferred in various herbicidal applications. In particular, it is found that these uracil-thiocyanate addition compounds have melting points usually greater than 300° C. which permits preparation of wettable powders having high concentrations of active ingredients and also makes sand-grinding of liquid formulations easier and more stable.

These novel addition compounds, as the corresponding uracils per se, can be used as general-purpose weed killers, as soil sterilants, in soil-foliage applications, and as selective weed killers for either pre- or post-emergence weed control. The compounds control both annual and perennial broadleaf weeds and grasses.

When applied pre-emergence, the compounds control such germinating broadleaf weeds as pigweed, lambs-quarters, mustard, chickweed, flower-of-an-hour, ragweed and such grass weeds as crab grass, water grass, giant foxtail, green foxtail and seedling Johnson grass.

In soil-foliage applications, the compounds control existing mixed annual and perennial vegetation composed of such broadleaf and grass weeds as crab grass, foxtail, water grass, quack grass, Bermuda grass, Johnson grass, brome grass, ragweed, cocklebur, pigweed, lamb's quarters, mare's tail, wild carrot, plantain and dandelion.

The broad spectrum herbicidal activity of these compounds suggests their use for the control or eradication of undesirable vegetation on industrial sites and on railroad ballast.

The concentration at which the compounds are to be used will naturally vary with the result desired, the type of vegetation, the formulation used, the mode of application, weather conditions, foliage density, and other similar factors. Since so many variables play a role, it is not possible to indicate a concentration suitable for all situations. Generally, however, when the compounds are used in pre-emergence treatments, they are applied at concentrations of from 0.25 to 35 pounds of active ingredient per acre. Concentrations of from 0.5 to 8 pounds per acre are preferred for selective weed control. When the compounds are used in soil-foliage applications, they are applied at concentrations of from 2 to 35 pounds per acre. More can be applied to control difficult-to-kill species under adverse conditions.

Preferred for use as herbicides are the addition compounds of formula 1 where R is a

radical
where

A is methyl or ethyl,
Y is hydrogen or methyl, and
Z is alkyl or 1 through 6 carbon atoms;
R₁ is halogen, or a branched or unbranched alkyl of 1 through 6 carbon atoms;

R_2 is hydrogen, or a branched or unbranched alkyl of 1 through 6 carbon atoms;
 R_3 is hydrogen;
 X is oxygen; and
 M is calcium;

with the proviso that R_1 and R_2 can be joined to form an alkylene bridge of 3 through 5 carbon atoms.

Especially preferred for use because of their herbicidal effectiveness are the calcium thiocyanate addition compounds with

3-(1-lower alkylethyl)-5-halogeno-6-methyluracils
 3-(2-lower alkylethyl)-5-halogeno-6-methyluracils
 3-(1-lower alkylisopropyl)-5-halogeno-6-methyluracils
 3-(cycloalkyl)-5-halogeno-6-methyluracils
 3-(cycloalkenyl)-5-halogeno-6-methyluracils
 3-(phenyl)-5-halogeno-6-methyluracils
 3-(bicycloalkyl)-5-halogeno-6-methyluracils
 3-(bicycloalkenyl)-5-halogeno-6-methyluracils
 3-(tricycloalkyl)-5-halogeno-6-methyluracils
 3-(tricycloalkenyl)-5-halogeno-6-methyluracils
 3-(lower alkyl)-5,6-alkyleneuracils and
 3-(cycloalkyl)-5,6-alkyluracils

In the foregoing list, "lower alkyl" means an alkyl radical containing 1 through 4 carbon atoms. 25

The herbicidal compositions of this invention incorporating the uracil-thiocyanate addition compounds hereof can readily be prepared for use by incorporating them with suitable adjuvants.

The amount of addition compound in such preparations can vary over a wide range according to need. Generally speaking, they will contain from about 0.5 to 95%, by weight of a uracil.

Powder and dust preparations can be made by mixing compounds of the invention with finely-divided solids such as talcs, natural clays, pyrophyllite, diatomaceous earth and synthetic fine silicas; flours such as walnut shell, wheat, redwood, soya bean and cotton seed; or inorganic substances such as magnesium carbonate, calcium silicate, calcium phosphate, sulfur and lime. These preparations are made by thoroughly blending the active ingredients and the solid. The particles in such preparations are preferably less than 50 microns in average diameter.

Granules and pellets can be made by mixing a finely-divided addition compound with a suitable clay, moistening this mixture with from 15 to 20% by weight of water, and then extruding the mass through a suitable die under pressure. The extrusions are cut into pre-determined lengths and then dried. These pellets can be granulated if desired.

Granules can also be prepared by spraying a suspension or solution of an addition compound onto the surface of a preformed granule or clay, vermiculite or other suitable granular material. When the active material is applied to granules from a water suspension, it is preferable that a binding agent such as goulac, dextrin, swollen starch, glue or polyvinyl alcohol be added to attach it more firmly to the granule surfaces.

Emulsifiable oil preparations can be made by dissolving a uracil-thiocyanate addition compound in an oil such as isophorone or cyclohexanone, and adding an emulsifying agent.

Aqueous suspensions of those addition compounds which are water-insoluble (less than 0.1% at room temperature) are prepared by first making a slurry of the active ingredient and suitable dispersing agent and then wet-grinding this slurry, by ball-milling or sand-grinding, until 90% of the particles of active ingredient are less than 10 microns in diameter.

Both of these liquid preparations can be diluted to the proper concentrations with water before application.

The herbicidal preparations, whatever physical form they take, can also contain a surface-active agent. The 75

surfactant renders the preparations readily dispersible in liquids and improves their action on waxy leaves and the like. For general application, surface-active agents are used in the preparations at concentrations of from about 1 to 10%, by weight. Levels of from 0.5 to 6 parts of surfactant for each part of uracil, however, give unusual and unexpected results. Preparations having these higher levels of surfactants show greater herbicidal effectiveness than can be expected from a consideration of the activity of the components used separately.

The term "surface-active agent" is intended to include wetting agents, dispersing agents and emulsifying agents. Surface-active agents suitable for use are set forth in "Detergents and Emulsifiers . . . Up-to-Date," 1962,

15 John W. McCutcheon, Inc., Morristown, New Jersey. Other surface-active agents which can be used in these preparations are listed in U.S. Patents 2,139,276, 2,412,510, 2,426,417, 2,655,477, and Bulletin E-607 of the Bureau of Entomology and Plant Quarantine of the U.S.

20 Department of Agriculture.

The preparations can also optionally contain adhesives such as gelatin, blood albumin and such resins as rosin alkyd resins. These increase retention and tenacity of deposits following application.

EXAMPLES

To aid in practicing the invention, the following examples are presented:

30 *Preparation of compounds*

EXAMPLE 1

One hundred fifty parts by volume of aqueous calcium thiocyanate solution (55-60%) are stirred at room temperature. To this are added 24.7 parts by weight of 5-bromo-3-isopropyl-6-methyluracil at room temperature. The temperature is increased from 25.5° C. to 27° C., and part of the uracil reactant dissolves, giving a milky solution. With additional stirring the product separates as a white paste.

After being stirred overnight, the product is filtered from the reaction mixture, washed with ether until the washings are colorless, and dried in a vacuum desiccator.

45 There are obtained 33 parts, by weight, of a white granular solid which melts above 300° C. It is soluble in acetone, acetonitrile and dimethylformamide.

This product is essentially pure 5-bromo-3-isopropyl-6-methyl 1/1 addition compound with calcium thiocyanate.

EXAMPLE 2

3-isopropyl-6-methyluracil (25.2 parts by weight) is added, in one portion, to a stirred aqueous solution of 150 parts, by volume, of calcium thiocyanate (55-60%). The temperature increases from 25° C. to 29° C. in four minutes and the mixture becomes paste-like.

After being stirred overnight, the product is filtered from the reaction mixture and washed with ether and n-pentane. The solid is dried overnight in a vacuum desiccator to give 48.5 parts of the 3-isopropyl-6-methyluracil 1/1 addition compound with calcium thiocyanate having a melting point greater than 300° C.

EXAMPLE 3

1,6-dimethyl-3-isopropyl (18.2 parts by weight) is added, in one portion, to a stirred aqueous solution of 150 parts by volume of calcium thiocyanate (55-60%). After being stirred overnight, the product is filtered from the mixture and washed with n-pentane, ether and finally benzene. The yield is 10.4 parts of the 1,6-dimethyl-3-isopropyluracil 2/1 addition compound with calcium thiocyanate having a melting point greater than 300° C.

EXAMPLE 4

3-cyclohexyl-5,6-trimethyleneuracil (23.4 parts by weight) is added, in one portion, to a stirred aqueous

solution of 150 parts by volume of calcium thiocyanate (55-60%). The temperature increases from 24 to 25.5° C.

The product is filtered from the solution after it has been stirred overnight, washed with n-pentane and ether, and then dried in a vacuum desiccator. There are obtained 33.5 parts by weight of the 3-cyclohexyl-5,6-trimethyluracil 2/1 addition compound with calcium thiocyanate. It is a tan powder, with a melting point greater than 300° C.

EXAMPLE 5

5-bromo-6-methyl-3-phenyluracil (28.1 parts by weight) is added to a stirred aqueous solution of 150 parts, by volume, of calcium thiocyanate (55-60%). After being stirred overnight, the 5-bromo-6-methyl-3-phenyluracil 1/1 calcium thiocyanate addition compound is isolated by filtration. It is washed with n-pentane and ether, and then dried in a vacuum desiccator.

EXAMPLE 6

Two hundred twenty-five parts, by volume, of an aqueous solution of barium thiocyanate (35-40%) are stirred at room temperature. To this, at room temperature, are added 24.7 parts, by weight of 5-bromo-3-isopropyl-6-methyluracil. The solution is stirred overnight and the 5-bromo-3-isopropyl-6-methyluracil 1/1 addition compound with barium thiocyanate is isolated by filtering, washing with ether, and drying in a vacuum desiccator over calcium chloride.

EXAMPLE 7

One hundred eighty-five parts, by volume, of an aqueous solution of strontium thiocyanate (45-50%) are stirred at room temperature. To this are added 24.7 parts by weight of 5-bromo-3-isopropyl-6-methyluracil at room temperature.

After being stirred overnight, the reaction mixture is filtered. The solid is washed with ether and n-pentane, and then dried in a vacuum desiccator over phosphorous pentoxide.

The product is essentially pure 5-bromo-3-isopropyl-6-methyluracil 1/1 addition compound with strontium thiocyanate.

Using the general procedures set out in Examples 1-7, one can prepare thiocyanate addition compounds with the uracils listed in the following table by reacting the uracil with the indicated thiocyanate, in the indicated proportions:

Uracil Reactant	Weight in Grams	Thio-cyanate	Volume and Strength Thiocyanate Solution Volume in ML.
3-benzyl-5-bromo-6-methyluracil	29.5	Ca	150 ml. (55-60%).
3-alkyl-6-methyluracil	16.6	Ca	150 ml. (55-60%).
3-propyl-6-methyluracil	16.4	Ca	150 ml. (55-60%).
3-cyclohexenyl-6-methyluracil	20.7	Ca	150 ml. (55-60%).
3-norbornylmethyl-6-methyluracil	23.3	Ca	150 ml. (55-60%).
3-norbornenylmethyl-6-methyluracil	23.1	Ca	150 ml. (55-60%).
3-(5-bromonorbornyl)-6-methyluracil	31.2	Ca	150 ml. (55-60%).
3-(5-chloronorbornenyl)-6-methyluracil	26.7	Ca	150 ml. (55-60%).
3-isobutyl-5-nitro-6-methyluracil	22.7	Ba	225 ml. (35-40%).
3-isopropyl-5-hydroxymethyl-6-methyluracil	19.8	Sr	185 ml. (45-50%).
3-cyclohexyl-5-methyluracil	20.8	Ca	180 ml. (55-60%).
3-isopropyl-5-methoxymethyl-6-methyluracil	21.2	Mg	150 ml. (55-60%).
3-isopropyl-5-bromo-6-bromomethyluracil	32.6	Ca	150 ml. (55-60%).
3-isopropyl-5-chloro-6-chloromethyluracil	23.7	Ca	150 ml. (55-60%).
1,3-diisopropyl-5-bromo-6-methyluracil	28.9	Ca	150 ml. (55-60%).
3-secbutyl-5-iodo-6-methyluracil	30.7	Ca	150 ml. (55-60%).
3-benzyl-5-chloro-6-methyluracil	25.0	Ca	150 ml. (55-60%).
3-pentyl-5-chloro-6-methyluracil	21.3	Ca	150 ml. (55-60%).
3-pentyl-5-bromo-6-methyluracil	25.8	Ca	150 ml. (55-60%).
3-tertbutyl-5-chloro-6-methyluracil	21.5	Ca	150 ml. (55-60%).
3-tertbutyl-5-bromo-6-methyluracil	25.0	Ca	150 ml. (55-60%).

Herbical formulations

EXAMPLE 8—AQUEOUS SUSPENSION

	Percent
3-sec.-butyl-5-bromo-6-methyluracil 1/1 addition compound with Ca(SCN) ₂	40.0
Attapulgite, hydrated	2.0
Goulac (sodium lignin sulfonate)	5.0
Water	53.0

Three hundred twenty-four grams of this mixture are mixed with 277 cc. of 20-30 mesh Ottawa sand. This mixture is agitated for 30 minutes at an agitator speed of 2700 r.p.m. in a sand-mill of the kind described in U.S. Patent 2,581,414

The resulting composition, after separation from the sand by centrifugation, is a thixotropic liquid whose solids do not cake densely on the bottom of the container on extended storage.

A portion of this composition can be extended with water to form a nonflocculated stable suspension containing 0.2-20%, by weight, of the active ingredient. When applied in 60 gallons of water to an industrial area, this mixture, at a rate of 15 to 20 pounds per acre of active ingredient, gives excellent control of such broadleaf and grass weeds such as crabgrass, foxtail, lamb's quarters, wild carrot, barnyard grass and seedling Johnson grass.

The 1:1 addition compounds in the following table can be similarly formulated and used in herbicidally equivalent amounts:

3-benzyl-5-bromo-6-methyluracil addition compound with Ca(SCN) ₂	
3-norbornylmethyl-6-methyluracil addition compound with Ca(SCN) ₂	
3-norbornenylmethyl-6-methyluracil addition compound with Ca(SCN) ₂	
3-(5-bromonorbornyl)-6-methyluracil addition compound with Ca(SCN) ₂	
3 - isopropyl-5-methoxymethyl-6-methyluracil addition compound with Mg(SCN) ₂	
3-isopropyl-5-bromo-6-bromomethyluracil addition compound with Ca(SCN) ₂	
3-isopropyl-5-chloro-6-chloromethyluracil addition compound with Ca(SCN) ₂	

EXAMPLE 9—EMULSIFIABLE OIL

	Percent
1,6-dimethyl-3-isopropyluracil 2/1 addition compound with Ca(SCN) ₂	10
Isophorone	85
Polyoxyethylene ether of alkylated phenol	5

This solution is extended with 200 gallons of water and applied at a rate of 25 pounds of active ingredient per acre for control of pepper grass, wild mustard, pigweed, crab grass and foxtail growing on an industrial site.

The addition compounds in the following table can be

Uracil Reactant	Weight in Grams	Thio-cyanate	Volume and Strength Thiocyanate Solution Volume in ML.
3-benzyl-5-bromo-6-methyluracil	29.5	Ca	150 ml. (55-60%).
3-alkyl-6-methyluracil	16.6	Ca	150 ml. (55-60%).
3-propyl-6-methyluracil	16.4	Ca	150 ml. (55-60%).
3-cyclohexenyl-6-methyluracil	20.7	Ca	150 ml. (55-60%).
3-norbornylmethyl-6-methyluracil	23.3	Ca	150 ml. (55-60%).
3-norbornenylmethyl-6-methyluracil	23.1	Ca	150 ml. (55-60%).
3-(5-bromonorbornenyl)-6-methyluracil	31.2	Ca	150 ml. (55-60%).
3-(5-chloronorbornenyl)-6-methyluracil	26.7	Ca	150 ml. (55-60%).
3-isobutyl-5-nitro-6-methyluracil	22.7	Ba	225 ml. (35-40%).
3-isopropyl-5-hydroxymethyl-6-methyluracil	19.8	Sr	185 ml. (45-50%).
3-cyclohexyl-5-methyluracil	20.8	Ca	180 ml. (55-60%).
3-isopropyl-5-methoxymethyl-6-methyluracil	21.2	Mg	150 ml. (55-60%).
3-isopropyl-5-bromo-6-bromomethyluracil	32.6	Ca	150 ml. (55-60%).
3-isopropyl-5-chloro-6-chloromethyluracil	23.7	Ca	150 ml. (55-60%).
1,3-diisopropyl-5-bromo-6-methyluracil	28.9	Ca	150 ml. (55-60%).
3-secbutyl-5-iodo-6-methyluracil	30.7	Ca	150 ml. (55-60%).
3-benzyl-5-chloro-6-methyluracil	25.0	Ca	150 ml. (55-60%).
3-pentyl-5-chloro-6-methyluracil	21.3	Ca	150 ml. (55-60%).
3-pentyl-5-bromo-6-methyluracil	25.8	Ca	150 ml. (55-60%).
3-tertbutyl-5-chloro-6-methyluracil	21.5	Ca	150 ml. (55-60%).
3-tertbutyl-5-bromo-6-methyluracil	25.0	Ca	150 ml. (55-60%).

similarly formulated and used, in herbicidally equivalent amounts:

3-allyl-6-methyluracil 1/1 addition compound with Ca(SCN) ₂	
3-propynyl-6-methyluracil 1/1 addition compound with Ca(SCN) ₂	
3-cyclohexenyl-6-methyluracil 1/1 addition compound with Ca(SCN) ₂	

9

1,3-diisopropyl-5-bromo-6-methyluracil 2/1 addition compound with $\text{Ca}(\text{SCN})_2$

EXAMPLE 10.—GRANULES

	Percent
5-bromo-3-sec.-butyl-6-methyluracil 1/1 addition compound with $\text{Ca}(\text{SCN})_2$	10
California Ca, Mg sub-bentonite	75
Anhydrous sodium sulfate	15

This composition is blended, micropulverized, pug-milled with about 20% water, moist-granulated and dried. It is then screened to 15-30 mesh granules.

At 15 pounds of active ingredient per acre, excellent control of such weeds as velvetleaf, chickweed, dandelion, pigweed, crab grass and cheat grass, growing along guardrails and around signboards, is obtained.

EXAMPLE 11.—PELLETS

	Percent
5-bromo-3-sec.-butyl-6-methyluracil 1/1 addition compound with $\text{Ca}(\text{SCN})_2$	11
Sodium sulfate, anhydrous	10
Mixture of sodium lignin sulfonate and wood sugars	13
Sub-bentonite	33
Kaolinite	33

These ingredients are mixed and micropulverized.

Eighteen percent of water is added to this preparation, with mixing. The mixture is then extruded through a pellet machine to give $\frac{1}{32}$ -inch pellets, which are then dried to constant weight.

Two hundred pounds per acre of this formulation are applied along a fire lane for the control of quack grass, barnyard grass, foxtails, crab grass, dandelion, wild mustard, pigweed and cocklebur.

The addition compounds in the following table can be similarly formulated and used, in herbicidally equivalent amounts

3-(5-chloronorbornenyl) - 6 - methyluracil 1/1 addition compound with $\text{Ca}(\text{SCN})_2$	40
3-isobutyl-5-nitro-6-methyluracil 1/1 addition compound with $\text{Ba}(\text{SCN})_2$	45
3-isopropyl-5-hydroxymethyl-6-methyluracil 1/1 addition compound with $\text{Sr}(\text{SCN})_2$	45

EXAMPLE 12.—WETTABLE POWDER

	Percent
5-bromo-3-isopropyl-6-methyluracil 1/1 addition compound with $\text{Ca}(\text{SCN})_2$	50
Sodium lignin sulfonate	3
Sodium alkyl aryl sulfonate	2

These ingredients are mixed and micropulverized to an average particle size below 50 microns.

The resulting wettable powder is applied at the rate of 8 pounds per acre (active) in 25 gallons water for the control of wild oats and cheatgrass along roadsides.

The 3-sec.-butyl-5-chloro-6-methyluracil 1/1 addition compound with $\text{Ca}(\text{SCN})_2$ and the 3-(2-ethylpropyl)-5-bromo-6-methyluracil 1/1 addition compound with

can be similarly formulated and used, in herbicidally equivalent amounts.

EXAMPLE 13.—WETTABLE POWDER

	Percent
3-cyclohexyl-5,6-trimethyluracil 2/1 addition compound with $\text{Ca}(\text{SCN})_2$	70
Attapulgite clay	17
Methylated cellulose	2
Sodium dioctyl sulfosuccinate	1

10

These ingredients are mixed and micropulverized to an average particle size below 50 microns.

Ten pounds (active) of this wettable powder in 40 gallons of water are sprayed around the edges of cultivated fields. Excellent control of foxtail, crab grass and barnyard grass is obtained.

The embodiments of the invention in which an exclusive property or privilege is claimed are:

1. A herbicidal composition comprising an adjuvant and, in an amount sufficient to exert herbicidal action, a compound of the formula

where

R is selected from the group consisting of alkyl of 1 through 10 carbon atoms, substituted alkyl of 1 through 8 carbon atoms, wherein said substituent is selected from the group consisting of bromide, chlorine, hydroxy, alkoxy, alkoxy carbonyl, dialkylamino, and cyano, aryl of 5 through 10 carbon atoms, substituted cycloalkyl of 3 through 12 carbon atoms, wherein said substituent is selected from the group consisting of chlorine, bromine, fluorine, phenyl-alkyl of 1 through 6 carbon atoms, chloroalkoxy of 1 through 5 carbon atoms, trifluoromethyl, 1,2-tetramethylene, and 1,2-trimethylene, arylalkyl of 5 through 13 carbon atoms, substituted arylalkyl of 5 through 13 carbon atoms, wherein said substituent is selected from the group consisting of chlorine, nitro, alkyl and alkoxy, alkenyl of 3 through 8 carbon atoms, alkynyl of 3 through 8 carbon atoms, cycloalkyl of 3 through 12 carbon atoms, substituted cycloalkyl of 3 through 12 carbons atoms, wherein said substituent is selected from the group consisting of bromine, chlorine, methoxy, and alkyl, cycloalkenyl of 4 through 12 carbon atoms, substituted cycloalkenyl of 3 through 12 carbon atoms wherein said substituent is selected from the group consisting of bromine, chlorine, methoxy, and alkyl, cycloalkyl alkyl of 4 through 13 carbon atoms, (substituted cycloalkyl)alkyl of 4 through 13 carbon atoms, wherein said substituent is selected from the group consisting of bromine, chlorine, methoxy and alkyl, cycloalkenyl of 5 through 13 carbon atoms, (substituted cycloalkenyl)alkyl of 5 through 14 carbon atoms, wherein said substituent is selected from the group consisting of bromine, chlorine, methoxy and alkyl;

R_1 is selected from the group consisting of hydrogen, halogen, nitro, hydroxymethyl, alkyl of 1 through 6 carbon atoms, and alkoxy methyl wherein the alkoxy portion thereof contains 1 through 4 carbon atoms; R_2 is selected from the group consisting of hydrogen, methyl, chloromethyl, and bromomethyl; R_3 is selected from the group consisting of hydrogen and alkyl of 1 through 4 carbon atoms; X is selected from the group consisting of oxygen and sulfur;

11

M is selected from the group consisting of magnesium, calcium, strontium and barium; and
n is selected from the group consisting of 1 and 2.

2. The composition of claim 1 wherein the adjuvant is a surfactant.

3. The composition of claim 1 wherein the adjuvant is a finely divided dispersible solid.

4. The composition of claim 1 wherein the adjuvant is a liquid.
